Primary Examiner—Ruth McInroy*Attorney, Agent, or Firm*—Diller, Ramik & Wight, PC[57] **CLAIM**

The ornamental design for protective headgear, as shown and described.

DESCRIPTION

FIG. 1 is a perspective view of a protective headgear showing our new design;

FIG. 2 is a side elevational view thereof and the opposite unillustrated side being a mirror image;

FIG. 3 is a front elevational view thereof;

FIG. 4 is a front elevational view of the interior front thereof;

FIG. 5 is a top plan view thereof; and,

FIG. 6 is a bottom plan view thereof.

The crosshatch surface shading in FIGS. 1-2 and 4-6 is understood to repeat throughout the indicated area.
